UNITED STATES PATENT OFFICE.

FRANK H. LEE, OF ELGIN, NEBRASKA.

TOY AEROPLANE.

1,359,078.

Specification of Letters Patent. Patented Nov. 16, 1920.

Application filed June 24, 1919. Serial No. 306,424.

To all whom it may concern:

Be it known that I, FRANK H. LEE, a citizen of the United States, residing at Elgin, in the county of Antelope and State 5 of Nebraska, have invented certain new and useful Improvements in Toy Aeroplanes, of which the following is a specification.

The invention relates to toys and has for its object to provide a toy aeroplane for 10 children, which may be pushed ahead of them as they run thereby revolving a wheel, which is belted to a propeller shaft, also to provide the device with a transversely disposed plane. 15 With the above and other objects in view the invention resides in the combination and arrangement of parts as hereinafter set forth, shown in the drawings, described and claimed, it being understood that changes 20 in the precise embodiment of the invention may be made within the scope of what is claimed without departing from the spirit of the invention.

The single figure shows the device in position for use.

Referring to the drawing, the numeral 1 designates an inclined bar, which is adapted to be held in substantially a 45 degree angle to the ground, and 2 a steering wheel 30 adapted to be grasped by the hands of the operator. The lower end of the bar 1 has secured thereto as at 3 bracket 4 and between said brackets is pivoted a wheel 5, which wheel is adapted to rest upon and 35 roll upon the ground. Secured to said wheel and adapted to rotate therewith is a pulley 6.

Secured at 7 to the bar 1 and extending 40 forwardly in substantially horizontal relation to the ground is a bar 8, the forward ends of which are provided with downwardly extending lugs 9, which lugs have rotatably mounted therein a shaft 10. Secured to the forward end of the shaft 10 is 45 a propeller 11 and also secured to said shaft 10 is a pulley 12. The shaft 10 is rotated by a belt 13, which passes around pulleys 6 and 12. Bar 8 is braced in relation to bar 1 by braces 14 and transversely disposed on 50 bar 8 and secured thereto by rivets 15 is a

plane 16, said plane being longitudinally braced by bars 17.

The operator grasps the steering wheel 2 then runs forwardly, wheel 5 being in engagement with the ground will cause the 55 pulley 6 to rotate and consequently through the medium of the belt 15, pulley 12 and its shaft will be rotated, which will cause the rotation of the propeller 11.

The invention having been set forth what 60 is claimed as new and useful is:—

1. A device of the character described comprising a frame, said frame being substantially triangular shaped, the apex of said frame being provided with handle 65 means, the lower end of one side of said triangular shaped frame having rotatably mounted therein a wheel, a shaft rotatably mounted in bearings on the other side of the triangular shaped frame, a propeller carried by said shaft, a pulley mounted on said shaft, a belt extending around said pulley and around a pulley on the wheel and a plane extending transversely across said frame and secured to one side thereof. 75

2. A device of the character described comprising a frame, said frame having a downwardly and forwardly extending handle member, a wheel pivoted in a bifurcation of said handle member and adapted to engage the ground, a pulley carried by said wheel, a downwardly extending horizontally disposed bar carried by the handle member, brace members between said bar and the handle member, the under face of the forward end of the bar being provided with downwardly extending lugs, a shaft 80 rotatably mounted in bearings of said lugs and provided with a propeller, a pulley carried by said shaft and at right angles to the pulley of the wheel, a belt extending around the wheel pulley and the shaft pulley, said belt forming means whereby the shaft and propeller will be revolved during a forward movement of the wheel while in engagement with the ground, said shaft pulley being disposed in vertical alinement with the wheel pulley. 85 90 95

In testimony whereof I affix my signature.
FRANK H. LEE.
